ILLINOIS, A CORPORATION OF DELAWARE

RAILWAY DRAFT RIGGING

Application filed February 13, 1928. Serial No. 253,881.

This invention relates to improvements in railway draft riggings.

In the operation of railway cars and more particularly freight cars, it is the present general practice to employ draft gears having a stroke of approximately $2\frac{3}{4}$ " available in both buff and draft. As is well known to those skilled in the art, draft gears on cars are constantly being subjected to greater and greater loads, due to the gradual increase in weight of individual cars and consequently greater loads carried thereby, the longer trains, and the more powerful locomotives. Up to the present time, railroad operators have not seen fit to permit any increase in the standard spacing of draft sills and consequently it is becoming more and more difficult to provide draft gears which will satisfactorily meet the constantly increasing demands of modern service.

One object of my invention is to provide a draft rigging for railway cars wherein greater shock absorbing capacity of the draft gear in buff is obtained, as compared with present day practice, by allowing a much longer compression stroke in buff than heretofore customary, while at the same time avoiding any increase in the draft movement of the gear which might otherwise produce undesirable train slack.

Another object of my invention is to obtain the above indicated advantages with a draft gear that may be used between standardly spaced sills and at the standard height above the rail.

A more specific object of my invention is to provide a draft rigging of the type above indicated wherein a yoke connector is introduced between the coupler and the main shock absorbing device, said connector being detachably associated with the shell of the shock absorbing device, the parts being so arranged as to introduce an easy draft action to facilitate starting of a train of cars.

Another specific object of the invention is to provide a connector of the type above indicated which is so designed that it will preserve the horizontal alinement of the coupler with the shock absorbing device in any condition of the parts.

Other objects of the invention will more clearly appear from the description and claims hereinafter following.

In the drawings forming a part of this specification, Fig. 1 is a vertical, longitudinal, sectional view of a portion of a railway car showing one embodiment of my invention. Fig. 2 is a horizontal, sectional view corresponding approximately to the line 2—2 of Fig. 1. Fig. 3 is a detailed vertical, sectional view corresponding to the line 3—3 of Fig. 1. Fig. 4 is a view similar to Fig. 1 illustrating another embodiment of the invention. Fig. 5 is a horizontal, sectional view corresponding to the line 5—5 of Fig. 4. And Fig. 6 is another view similar to Figs. 1 and 4, illustrating a still further embodiment of the invention.

Referring first to the construction illustrated in Figs. 1, 2 and 3, 10—10 denote the usual draft sills of a railway car which may constitute a part of the center sills. A bolster is indicated at 11, the same having a center filler casting 12 which provides a front stop wall 13 acting as the rear stop means of the shock absorbing device. Secured to the inner faces of the draft sills are front stop lugs 14—14 of usual construction. The draft sills are united to an end sill 15 and the opening at the end of the sills for the reception of the coupler is suitably reinforced by a casting 16 and to which is secured the usual carry iron 17 for supporting the coupler and yoke connector.

In carrying out my invention, I use a coupler connector indicated generally by the reference character A; a friction shock absorbing device indicated by the reference character B; a front follower C; and a secondary or auxiliary cushioning unit D. The connector A is detachably connected with the coupler 18 by the usual coupler key 19 that works in slots 20 provided in the draft sills as shown in Fig. 2. Suitable saddle plates 21 and 22 are employed to support the shock absorbing device and associated parts.

The shock absorbing device B may be of any suitable type, having a relatively long compression stroke. As shown, it comprises a combined friction shell and spring cage

casting 23 indicated conventionally and the usual wedge and friction elements are also indicated conventionally at 24, the wedge thereof being adapted to directly engage a wear plate 25 secured to the stop wall 13 of the bolster center filler.

At its outer or front end, i. e., the end nearest the coupler, the shell casting 23 is provided with a rectangular or box-like extension 26, the latter having vertical side walls 27-27 and horizontal top and bottom walls 28-28, the interior faces of all of said walls being recessed to provide a cylindrical opening 29 within which is accommodated the resistance unit D, in this instance shown as a heavy coil spring. The outer surfaces of the walls 27 of said extension are rounded, as indicated at 30, the curvature being concentric with a vertical center line passing through the extension, as indicated at 31. The length of the extension 26 is such as to leave a space of about $1\frac{1}{2}$ " or such movement as may be desired for draft, between it and the follower C, for the purpose hereinafter described.

The connector A, preferably in the form of a casting, is provided with an elongated horizontal bottom wall 32, side walls 33-33 and a top wall 34. The bottom wall 32 extends horizontally for an appreciable distance, both forwardly and rearwardly of the carry iron 17 and is then extended downwardly as indicated at 132 and thence horizontally as indicated at 232, this being done so as to provide a deeper section where the inner end of the connector fits over the extension 26 of the shell 23.

The side walls 33 are laterally flared, as best shown in Fig. 2. Said walls 33 are recessed as indicated at 133, to receive therein the front follower C and permit of limited relative movement between said follower and connector A, as best shown in Fig. 1. Rearwardly of the openings 133, the side walls are made of approximately arcuate form, as indicated at 233, and so spaced as to be slidable over the side walls 27 of the shell 23.

The connector and extension 26 of the shell are detachably and, in the form shown, pivotally connected by two pins 40-40, each of which is headed and is entered into aligned slots in the connector A and extension 26 from the interior opening 29, as shown in Fig. 3. The heads of the pins 40 are received in suitable countersinks 41, as there shown. When thus assembled and the spring unit D introduced, it is evident that the pins 40 will be held in proper position and the parts can only be disassembled when the follower C is taken out and then the spring unit D. The rear edges of the top and bottom walls 34 and 32 of the connector are made straight, as indicated at 42.

In a buffing action, the coupler 18 acts directly upon the follower C and the front spring unit D will first be compressed and

until the follower C engages with the front edges of the extension 26 of the friction shell, it being observed that the slots in the side walls of the connector A are sufficiently elongated to permit the coupler to move independently of the connector A in this direction. After the follower C has engaged the outer end of the extension 26, the combined friction shell and spring cage 23 will be forced rearwardly, thus actuating the friction shock absorbing device proper. In actual practice, the total stroke in the buff movement will approximate $5\frac{1}{2}$ " to 6" so to provide a much longer travel than now customary and thereby absorb a greater shock without increase of ultimate stresses. In draft, forward movement of the coupler 18 will pull the key 19 therewith and the latter in turn will pull the connector A. Inasmuch as the latter is pivotally connected to the shell extension 26, the latter will also be pulled forwardly, thus compressing the spring unit D against the follower C. In this draft action, however, there will be no actuation of the friction device proper and the amount of draft action will be limited to the space left between the forward end of the extension 26 and the follower C. This amount will preferably be somewhat less than the usual draft action of $2\frac{3}{4}$ " but in any event will be appreciably less than the buff stroke so as to avoid undesirable train slack.

By extending the bottom wall 32 of the connector A to a point approximately out to the head of the coupler and attaching the connector A to the friction device as above described, it will be evident that an elongated bearing or support for the coupler shank is obtained in all positions of the parts and hence drooping or falling down of the outer end of the coupler is prevented and horizontal alinement of the coupler and draft gear preserved.

By providing a pivotal connection between the connector A and shell extension 26, an easier lateral movement of the coupler is thereby obtained, as will be evident.

Referring next to the modification of the invention shown in Figs. 4 and 5, the arrangement of draft sills, end sill, bolster, carry iron and saddle plates, is the same. In said modification, the friction shock absorbing device is indicated at E, the yoke connector at F, the auxiliary cushioning device or unit at G and the front follower at H.

The connection between the connector F and coupler 118 is the same as in the first described modification. The connection between the coupler and the shell 123 of the shock absorbing device E is somewhat different, the pivotal form being omitted. The shell 123 is formed at its front or outer end with transversely extending grooves or recesses 50-50 formed in the upper and lower walls thereof and the upper and lower walls

of the connector F are modified so as to provide upper and lower rearward extensions 51-51, each of the latter being provided with an inturned heavy flange or lug 52 that fits loosely within the corresponding recess 50 of the shell 123. Preferably the width of the lugs 52 in a horizontal direction is somewhat less than the width of the slots 50 so as to allow for a slight amount of lost motion between the connector F and shell 123 during any buff movement of the connector F, and to allow for lateral movement of the coupler. As will be understood, the connector F and shell 123 are connected by sliding the connector F transversely of the shell and, when the parts are between the draft sills, they will be retained in assembled position.

In the modification of Figs. 4 and 5, instead of providing an integral projection on the front or forward end of the shell, I provide an equivalent structure in the form of a box-like spring follower 126 which fits loosely between the side and top and bottom walls of the rear portion of the connector F, as best shown in Fig. 5. The auxiliary spring unit G is received within the follower casting 126 and is compressed between the follower H and the rear wall of the follower 126 during either a buff or draft action, as will be obvious. The length of the follower 126 horizontally and parallel to the axis of the gear is made less than the distance between the follower H and the forward end of the shell 123, the difference being made to correspond to the desired amount of relatively short draft action.

In a buff action, it will be evident that the coupler will actuate the follower H directly and the first resistance will be that of the spring unit G until the follower H engages the spring follower 126. Thereafter, the buffing movement will actuate the friction shock absorbing device, the limit of the latter being determined by engagement of the rear end of the shell 123 with the bolster. In draft, there will be no actuation of the friction shock absorbing device proper and the cushioning effect will be obtained through the spring unit G and the amount of draft action limited by the spring follower 126 engaging the follower H, similar to the action in the first described modification.

Referring to the modification shown in Fig. 6, the arrangement of draft sills, coupler and bolster will be the same. In this modification, the shell 223 of the shock absorbing device proper is provided with an integral forward extension 226, the latter having an intermediate partition 60 which forms the rear abutment for the auxiliary front spring unit J which is interposed between said partition 60 and the front follower K. In this form, the main spring of the friction shock absorbing device proper, indicated at 61, is extended through what would

normally be the rear wall of the shell 223 and bears against said partition 60, thus permitting of a somewhat longer main spring in the friction shock absorbing device.

The yoke connector L is attached to the shell 223 by means of upper and lower, transversely extending keys 62-62 which are entered through aligned slots in the said walls of the connector L and which pass loosely through upper and lower recesses 63-63 formed in the top and bottom portions of the extension 226. Preferably, a slight amount of play is left between the keys and the extension in a buff movement. The extension 226 will be of such length as to provide for the desired amount of relatively short draft travel, said extension and preferably also the front edges of the side walls of the connector L coming into engagement with the follower K to limit the draft action. The operation is the same as in the case of the two modifications previously described, i. e., first a compression of the spring unit J and thereafter compression of the friction shock absorbing device during a buff action, the total stroke being the sum of the compression strokes of the spring J and friction device. The draft action actuates the spring J only and the amount is limited, as above described.

Although I have herein shown and described what I now consider the preferred manner of carrying out my invention, the same is merely illustrative and I contemplate all changes and modifications that come within the scope of the claims appended hereto.

I claim:

1. In a draft rigging, the combination with draft sills; of front and rear stop acting means; a main shock absorbing device having a shell; a yoke connector, the latter being attached at its inner end to the outer end of said shell and adapted for the reception of a coupler shank and attachment thereto, said connector having a bottom wall extending forwardly to a point adjacent the coupler head and on which the coupler shank is sustained; and a secondary cushioning device of relatively short compression stroke interposed between the front end of said shell and the inner end of the coupler.

2. In a railway draft rigging, the combination with draft sills; of front and rear stop acting means; a front follower; a main shock absorbing device of comparatively long stroke and including a shell; a yoke connector detachably connected to said shell; a secondary shock absorbing device interposed between the front end of said shell and said follower, the buff stroke of said rigging being equal to the sum of the compression stroke of both of said shock absorbing devices; and means limiting the draft stroke of said connector to an amount less than the

buff stroke, said main shock absorbing device being inactive during draft.

3. In a railway draft rigging, the combination with draft sills and body bolster, of front stop acting means, a main shock absorbing device engageable with said bolster and adapted to be compressed thereagainst in a buff action, said device including a friction shell; a front follower; a yoke connector detachably connected to said shell; and a secondary shock absorbing device interposed between the front end of said shell and follower whereby, in buff, both of said devices are adapted to be actuated and, in draft, said auxiliary shock absorbing device, only.

4. In a draft rigging for cars, the combination with draft sills; of a main shock absorbing device including a casing and cooperating friction devices, said casing being closed at the forward end by a transverse wall and having a friction shell section at the rear end thereof with which said friction devices cooperate; front and rear stop-acting means; a connector attached at one end to said casing to bodily move the same in draft, said connector being operatively joined to a coupler and movable with the latter in draft; and a separate cushioning device interposed between said transverse wall of the casing and the inner end of the coupler and actuated by bodily movement of said casing in draft.

5. In a draft rigging, the combination with draft sills; of front and rear stop-acting means; a front follower; a friction shock absorbing device including a shell having a fixed abutment wall at the forward end; a yoke connector detachably joined to the shell to effect movement of the latter in draft, said yoke connector being attached to the coupler; a secondary shock absorbing device of relatively short stroke interposed between said follower and the fixed abutment wall of said shell, adapted to be compressed therebetween upon relative approach thereof, and transmitting the actuating force directly from said follower to the shell in buff; and means for limiting the draft movement of the coupler and connector to an amount less than the buff movement thereof.

6. In witness that I claim the foregoing I have hereunto subscribed my name this 4th day of February, 1928.

ERNEST R. SCHULZ.
